UNITED STATES PATENT OFFICE.

WILLIS P. FULTON, OF BARNSTON, NEBRASKA.

SACK-BALER.

1,147,500.

Specification of Letters Patent. Patented July 20, 1915.

Application filed July 25, 1914. Serial No. 853,099.

To all whom it may concern:

Be it known that I, WILLIS P. FULTON, a citizen of the United States, residing at Barnston, in the county of Gage and State of Nebraska, have invented new and useful Improvements in Sack-Balers, of which the following is a specification.

This invention is an improved sack baler for baling or arranging in bundles, sacks 10 such as cement sacks, or grain sacks after they have been emptied and for shipment back to the mill or factory, the object of the invention being to provide an improved machine of this character which is extremely 15 cheap and simple, is strong and durable, which is adapted to be operated manually and by means of which empty sacks may be expeditiously arranged in bundles for shipment.

20 The invention consists in the construction, combination and arrangement of devices hereinafter described and claimed.

In the accompanying drawings:—Figure 1 is a perspective view of a sack baler constructed in accordance with my invention showing the same in initial position with its gripping arms open. Fig. 2 is partly an end elevation and partly a transverse sectional view of the same showing the arms 30 open in full lines and in closed or baling position in dotted lines.

In the form of the invention here shown a frame 1 is provided which comprises a pair of side bars 2, and a pair of connecting end bars 3 and has supporting legs 4 at its corners which serve to support the frame horizontally and at a suitable height above the ground. Bearing blocks 5 are arranged on the end bars 3 and at the rear end of the 40 frame there is a vertical standard 6 the lower end of which is secured on the center of one of the end bars. Said standard is provided with a suitable number of spaced adjusting openings 7. At the front end of the 45 frame there is a standard 8, which is pivotally connected as at 9 to the front cross bars so that said standard may be turned to an upright position or turned downwardly to a horizontal position at will and 50 this standard is provided on one side with a series of adjusting notches 9 which correspond in number and position with the adjusting openings 7 of the standard 6.

A pair of shafts 10—11 are arranged 55 longitudinally of the frame and near the center thereof and are mounted in the bear-

ings 5. The shaft 10 is longer than the shaft 11 and is provided at its front end with a crank handle 12. Each shaft is provided with a gear 13, said gears engaging each other and hence when the shaft 10 is turned the shaft 11 is also turned but in the reverse direction. A pawl 14 is provided which is pivotally mounted on the front bearing 5 and may be engaged with 60 the gear of the shaft 10 to lock the shafts against rotation. Initially this dog or pawl is disengaged. Each shaft is provided with compressing and binding arms 15 which are substantially semi-circular in shape and extend in opposite directions from the respective shafts, a suitable number of said arms being provided on each shaft and said arms being arranged at a suitable distance apart.

In the operation of my invention, assuming that the machine is in initial position with the binding arms of the respective shafts apart or open, the sacks to be arranged in a bale or bundle are laid longitudinally of the machine and on the shafts 65 and between the binding arms and when a suitable number of the shafts have been thus placed a rod 16 is placed on them with one end engaged in one of the openings 7 of the standard 6 and the other end engaged in one 70 of the notches of the standard 8, said rod serving to hold the sacks firmly down upon the shaft and binding arms. Suitable tie wires or cords are arranged transversely of the frame and across the shafts and under 75 the lowermost sack. The operator then by means of the crank handle 12 turns the shafts so as to cause the binding arms to move toward each other and in so doing to gather and compress the sacks into a substantially cylindrical bundle or bale and to hold the same thus firmly compressed by engaging the dog 14 with one of the gears 13 while the bundle is tied by means of the 80 cords or wires. The rod 16 is then withdrawn, the dog released from the gear and the shafts turned in the reverse direction so as to cause the binding arms to release the 85 bundle or bale which may then be taken out.

Having thus described my invention, I 90 claim:—

1. A baler of the class described comprising a supporting frame, bearings on the upper sides of said supporting frame, a pair of parallel shafts mounted on said bearings 110 and hence arranged also on the upper side of the frame, gears connecting said shafts

for simultaneous partial rotation in reverse directions, means to turn one of said shafts and oppositely extending and reversely curved binding arms on said shafts, standards at the ends of said frame and extending upwardly therefrom and above said shafts and a rod carried by said standards and arranged above said shafts.

2. A baler of the class described comprising a supporting frame, bearings on the upper sides of said supporting frame, a pair of parallel shafts mounted on said bearings and hence arranged also on the upper side of said frame, gears connecting said shafts 15 for simultaneous partial rotation in reverse

directions, means to turn one of said shafts, and oppositely extending and reversely curved binding arms on said shafts, standards at the ends of said frame and extending upwardly therefrom and above said shafts, 20 said standards having adjusting openings and a rod for insertion in any of said openings so that said rod may be arranged at any desired distance above the shafts.

In testimony whereof I affix my signature in presence of two witnesses.

WILLIS P. FULTON.
